UNITED STATES PATENT OFFICE.

DAVID FREDRICK BALDAUF, OF EDEN, NEW YORK.

CAN-FILLING MACHINE.

SPECIFICATION forming part of Letters Patent No. 651,690, dated June 12, 1900.

Application filed April 12, 1900. Serial No. 12,587. (No model.)

To all whom it may concern:

Be it known that I, DAVID FREDRICK BALDAUF, a citizen of the United States, and a resident of Eden, in the county of Erie and State of New York, have invented a new and Improved Can-Filling Machine, of which the following is a full, clear, and exact description.

This invention relates to improvements in machines for filling cans with material—such, for instance, as string-beans; and the object is to provide a machine for this purpose of simple construction and so arranged that a large number of cans may be quickly and uniformly filled.

I will describe a can-filling machine embodying my invention and then point out the novel features in the appended claims.

Reference is to be had to the accompanying drawings, forming a part of this specification, in which similar characters of reference indicate corresponding parts in all the figures.

Figure 1 is a sectional elevation of a can-filling machine embodying my invention. Fig. 2 is a plan view, and Fig. 3 is an end view.

The machine comprises a frame 1, at the ends of which vertically-movable rods 2 are arranged. The rods 2 are connected to a cross-bar 3, which has projecting ends movable in guides 4, connected to the uprights of the frame. At the upper ends these bars 2 are connected by a cross-bar 5, having hinge connections 6 with a platform 7, arranged above the frame. Having bearings in the end uprights of the frame are shafts 8 9, and on these shafts are cams 10, adapted to engage with the lower ends of the bars 2 to impart rocking motion to the platform 7. It will be noted that the cams on the shafts are extended in diametrically-opposite directions, so that when the shafts are turned one end of the platform 7 will be moved upward, while the other end moves downward, the hinges forming the fulcrum for said movements. The shafts are geared together, as here shown, by means of sprocket-wheels 11 12 and a sprocket-chain 13. Motion may be imparted to the shafts in any desired manner. I have here shown one of the shafts as provided with a fixed pulley 13^a to receive a band, and a loose pulley 14, upon which the band may be moved

when it is desired to stop the operation of the machine without stopping the motive power.

Removably placed on the platform 7 is a tray 15, designed to contain the cans to be filled. The tray may be made to contain any desired number of cans—say, for instance, one hundred or more. Removably placed in the upper portion of the tray is a hopper 16, having in its bottom a series of openings 17 equal in number to the number of cans contained in the tray and each having a diameter substantially equal to the opening of the can underneath it. The hopper may be held in place by any suitable means. I have here shown springs 18, connected at the lower ends to the platform 7 and having hook-shaped upper ends to engage over the ends of the hopper.

In operation the beans or other material to be canned are placed in the hopper. Then when motion is imparted to the shafts 8 and 9 the platform carrying the tray and hopper will be rocked up and down alternately at the opposite ends, as before mentioned. This movement will cause the material in the hopper to spread out evenly and pass through the holes 17 into the cans. After filling the cans the hopper may be removed, and then the filled cans are to be removed.

A machine made in accordance with my invention is of very simple construction, and it is easily operated either by hand or by a steam or other motor.

Having thus described my invention, I claim as new and desire to secure by Letters Patent—

1. A canning-machine, comprising a frame, shafts mounted in said frame and geared together, cams on said shafts extended in opposite directions, frames at the ends of the machine-frame and adapted to be moved vertically by said cams, a platform having swinging connection with said end frames, a tray adapted to hold cans to be filled, and a hopper having openings through which material may pass into the cans, substantially as specified.

2. A canning-machine, comprising a platform, means for causing a rocking motion thereof, a tray removably arranged on the platform, a hopper having openings through its bottom, and spring-yielding hooks con-

nected at one end to the platform and adapted to engage with the said hopper, substantially as specified.

3. A canning-machine, comprising a frame, shafts mounted in said frame and geared together, cams on said shafts, the cams on one shaft being extended in an opposite direction to the cams on the other shaft, frames adapted to be moved upward by said cams, a platform having hook connections at its ends with said moving frame, a tray supported on the platform and adapted to contain a number of cans to be filled, and a hopper having openings

through its bottom equal in number to the number of cans to be arranged in the tray, the said openings being of a diameter substantially that of the openings in the cans, as specified.

In testimony whereof I have signed my name to this specification in the presence of two subscribing witnesses.

DAVID FREDRICK BALDAUF.
